UNITED STATES PATENT OFFICE.

ARTHUR G. ROGERS, OF MERIDEN, CONNECTICUT, ASSIGNOR TO C. ROGERS & BROS., OF SAME PLACE.

DESIGN FOR A SPOON OR FORK HANDLE.

SPECIFICATION forming part of Design No. 19,840, dated May 13, 1890.

Application filed March 24, 1890. Serial No. 345,167. Term of patent 14 years.

To all whom it may concern:

Be it known that I, ARTHUR G. ROGERS, of Meriden, in the county of New Haven and State of Connecticut, have invented a new Design for Spoon and Fork Handles, (A;) and I do hereby declare the following, when taken in connection with accompanying drawings, to be a full, clear, and exact description of the same, and which said drawings constitute part of this specification, and represent, in—

Figure 1, a face view of a fork, showing the handle, the same being represented in broken lines as a spoon; Fig. 2, an edge view.

This invention relates to a design for the ornamentation of the handles of spoons, forks, and like articles; and the design consists in the ornamentation of the handle, as shown in the accompanying illustration and hereinafter described.

On the face of the handle is the representation of a series of ribs running from a central line on the handle oppositely inclined to the edges of the handle. The surface of these ribs may be ornamented; but such ornamentation constitutes no part of the present design, the essential feature of the design being the representation of a series of ribs running from a central line on the handle in oppositely oblique directions to the edge of the handle.

I claim—

The design for spoon and fork handles, as herein illustrated and described.

ARTHUR G. ROGERS.
